2,238,377

UNDERCUTTER

Edward S. Strang, Long Beach, Calif.

Application September 9, 1939, Serial No. 294,119

6 Claims. (Cl. 255—76)

This invention relates to an undercutter, particularly applicable for use in wells, a portion of the well bore having casing therein.

The purpose of my invention is to provide a novel undercutter, which can be run into a bored hole through the casing, and when moved out of the casing, the arms of the undercutter are sprung outwardly to undercut the bore of the well in a rapid and effective manner.

An object of my invention is to provide a novel undercutter in which the arms, upon each of which a cutter is mounted, are forced outwardly into undercutting position by means of a rubber block, which bears against the arm.

Another object is to provide a novel undercutter of the character stated, in which the extensible arms are so mounted in the body as to be effectively supported while carrying the strain of the cutting operation, and further to provide a novel means of a circulating mud around the cutters.

A feature of my invention is to provide a novel antifriction roller or bearing, which bears against the casing while the tool is being lowered in the well.

Other objects, advantages and features of invention may appear from the accompanying drawing, the subjoined detailed description, and the appended claims.

In the drawing the single figure is a transverse, sectional view of my undercutter, parts of the undercutter being left in elevation.

Referring more particularly to the drawing, my undercutter comprises a body 1, from the upper end of which a threaded pin 2 extends to receive the drill pipe 3. A pin or other suitable threaded coupling 4 depends from the body 1, and a pilot bit 5 screws onto the pin or coupling 4. The body 1 is provided with a plurality of recesses 6. Each of these recesses is adapted to receive a cutting arm 7. Each of the cutting arms 7 is journaled on a pin 8, which is seated in the body 1. An arcuate seat 9 is provided in the body 1, and the upper end of each of the arms 7 is curved as shown at 10, so as to fit in the seat 9. Thus, during the strain of the cutting operation, the arms 7 can bear against the seat 9, thus relieving the pin 8 of an excessive load. A toothed cone cutter 11 is mounted adjacent the outer end of each of the arms 7 and is rotatably mounted on the arm to enable the cone cutter to rotate and cut into the formation during the operation of the tool.

A ball or roller bearing 12 is mounted in each of the arms 7 and protrudes slightly from the

outer surface of the arm so that when the tool is being lowered into the well through the casing, this roller or ball bearing will bear against the casing, and will reduce the frictional resistance to the downward movement of the tool. A rubber block 13 is positioned between the inner face of each arm 7 and the inner surface of the recess 6, substantially as shown. This rubber block when permitted to expand will force the arm 7 outwardly to the position shown in the drawing. When the tool is being run into the hole through the casing, the arms 7 are forced inwardly, and the rubber blocks 13 are compressed. A bolt 14 extends through the arm 7 and the rubber block 13, and is threaded into the body of the tool 1. Thus, the rubber blocks are held in position in the tool.

The head of the bolt 14 fits into a counter-bore 15 in the arm 7, thus permitting the arm to swing inwardly or outwardly while the tool is being run into the hole through the casing or while the tool is in cutting position. The head of the bolt also acts as a stop to prevent the arm 7 from moving outwardly more than a predetermined distance.

A circulation bore 16 extends vertically through the undercutter and circulation holes 17 extend from the bore 16 into each of the recesses 6. The holes 17 are preferably directed downwardly at an angle so that the circulating mud is directed against each of the toothed comb cutters 11. As shown in the drawing, the holes 17 are preferably opposite the cutters 11 when the cutters are in expanded position. The operation of my novel undercutter will be apparent from the previous description.

Having described my invention, I claim:

1. An undercutter comprising a body, said body being adapted and arranged to be mounted on drill pipe, said body having a recess in the side thereof, a cutter arm mounted in said recess, a pin extending through the arm and seated in the body whereby the arm is held in position, a cutter journaled on said arm adjacent the lower end thereof, and a rubber block positioned between said arm and the body of the undercutter, said rubber block urging the arm outwardly, an arcuate seat formed in the body within said recess, said arm being adapted and arranged to bear against said seat.

2. An undercutter comprising a body, said body being adapted and arranged to be mounted on drill pipe, said body having a recess in the side thereof, a cutter arm mounted in said recess, a pin extending through the arm and seated in the

body whereby the arm is held in position, a cutter journaled on said arm adjacent the lower end thereof, and a rubber block positioned between said arm and the body of the undercutter, said rubber block urging the arm outwardly, a bolt extending through said rubber block and into the arm, the head of said bolt engaging the arms to limit outward movement thereof.

3. An undercutter comprising a body, said body being adapted and arranged to be mounted on drill pipe, said body having a recess in the side thereof, a cutter arm mounted in said recess, a pin extending through the arm and seated in the body whereby the arm is held in position, a cutter journaled on said arm adjacent the lower end thereof, and a rubber block positioned between said arm and the body of the undercutter, said rubber block urging the arm outwardly, an arcuate seat formed in the body within said recess, said arm being adapted and arranged to bear against said seat, a bolt extending through said rubber block and into the arm, the head of said bolt engaging the arms to limit outward movement thereof.

4. An undercutter comprising a body, a plurality of recesses extending into the side of said body, an arm mounted in each of the recesses, a pin extending through each of the arms and mounted in the body, a toothed cutter rotatably mounted on each of the arms adjacent the lower end thereof and on the inside of the arm, a rubber block positioned between the inner face of each of the arms and the body, said rubber blocks urging the arms outwardly into cutting position, and a bolt extending through the arms

and rubber block and secured in the body, whereby the rubber blocks are held in position.

5. An undercutter comprising a body, a plurality of recesses extending into the side of said body, an arm mounted in each of the recesses, a pin extending through each of the arms and mounted in the body, a toothed cutter rotatably mounted on each of the arms adjacent the lower end thereof, a rubber block positioned between the inner face of each of the arms and the body, said rubber blocks urging the arms outwardly into cutting position, and a bolt extending through the arms and rubber blocks and secured in the body, whereby the rubber blocks are held in position.

10 15

10 said body having a vertical circulation bore extending into the same and a circulation hole extending from the bore into each of said recesses.

6. An undercutter comprising a body, a plurality of recesses formed in the side of said body, an arm mounted in each of the recesses, a pin extending through each of the arms and mounted in the body, a cutter rotatably mounted on each of the arms adjacent the lower end thereof, said cutter being mounted on the inside of the arms, 20 25 a rubber block positioned between the inner face of each of the arms and the body, said rubber blocks urging the arms outwardly into cutting position, said body having a vertical circulation bore extending into the same and a circulation hole extending from the bore into each of the recesses, said circulation holes being positioned above the cutters and directing fluid towards the cutters.
